DESIGN FOR A HAND BAG

Isidore Lending, New Bedford, Mass., assignor to Sol Mutterperl, Inc., New Bedford, Mass.

Application May 7, 1935, Serial No. 56,719

Term of patent 3½ years

To all whom it may concern:

Be it known that I, Isidore Lending, a citizen of the United States, residing at New Bedford, in the county of Bristol and State of Massachusetts, have invented a new, original, and ornamental Design for Hand Bag, of which the following is a specification, reference being had to the accompanying drawing, forming part thereof.

Figure 1 is a perspective view of the hand bag in closed position showing my new design; and

Figure 2 is a perspective view of a hand bag in an open position on a slightly enlarged scale of the hand bag shown in Figure 1 with the surface ornamentation omitted.

I claim:

The ornamental design for a hand bag, as shown and described.

ISIDORE LENDING.
